BROOM WITH METAL HANDLE

Alfred L. Le Febvre, Windsor, Conn., assignor to
 The Fuller Brush Company, Hartford, Conn., a
 corporation of Connecticut

Application December 21, 1950, Serial No. 202,117

2 Claims. (Cl. 15—171)

1

The invention relates to a broom and more particularly to a broom having a head comprising two oppositely disposed metallic plates.

The object of the invention is to provide a broom of the type mentioned having simple, effective and inexpensive means for rigidly connecting the two plates of the head with a metallic handle and with each other.

Other objects of the invention will be apparent from the drawing and from the following description and claims.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing:

Fig. 1 is a side view of a broom embodying the invention.

Fig. 2 is an edge view of a portion of the broom shown in Fig. 1.

Fig. 3 is a transverse sectional view taken along the line 3—3 of Fig. 1.

Fig. 4 is a transverse sectional view taken along the line 4—4 of Fig. 1.

Fig. 5 is a longitudinal sectional view taken along the line 5—5 of Fig. 1.

Referring to the drawing, 10 represents a mass of suitable fibers arranged and cut to constitute the body of a broom. The fibers are connected with each other at their upper end portions by means of a plastic compound or by means of stitching or otherwise in accordance with conventional practice.

For holding the broom body 10 a head is provided which comprises two similar oppositely disposed sheet metal plates 12 and 14. The two plates are shaped at their lower portions to embrace and enclose the upper portion of the broom body, the said plates preferably overlapping each other at their edges as shown in Fig. 3. The two plates are shaped at their upper portions to provide two oppositely disposed at least partly cylindrical longitudinal sockets 16 and 18 as shown in Fig. 4. The lower portions of the two plates 12 and 14 are connected with each other and with the broom body 10 by means of rivets 20, 20. The rivets extend through the broom body.

A longitudinal metallic cylindrical handle 22 is provided which is preferably tubular, the exterior diameter of the handle being such that it is adapted at its lower end portion to enter

2

and fit the sockets 16 and 18 in the plates 12 and 14. The socket 16 of the plate 12 is welded to the lower portion of the handle 10, as indicated at 24, and the socket 18 of the plate 14 is welded to the opposite side of the lower portion of the handle, as indicated at 26. The welding at 24 and 26 serves to rigidly connect the handle to the upper portions of the two plates and also serves in conjunction with the handle to rigidly connect the upper portions of the two plates with each other. It will be observed that after welding the two plates and the handle constitute a rigid unitary structure.

For covering the upper ends of the sockets 16 and 18 of the two plates a flanged collar 28 is preferably provided. The collar has a central hole which fits the handle and the diameter of the flange of the collar is such that it is approximately fits the upper ends of the outer peripheries of the sockets 16 and 18. The walls of the sockets are provided respectively with small oppositely disposed holes or depressions 30 and 32. When the collar 28 is in place, its flange is deformed at opposite sides thereof to provide projections which extend into the holes or depressions 30 and 32 to hold the collar in place.

The invention claimed is:

1. In a broom, the combination of a broom body comprising fibers, a head comprising two oppositely disposed plates in fixed relationship with each other and having their lower portions embracing and fitting the upper portion of the head, the upper portions of the said plates being shaped to provide two oppositely disposed at least partly cylindrical longitudinal sockets, means for connecting the lower portion of the plates of the head with the upper portion of the broom body, and a longitudinal metallic cylindrical handle the lower portion of which is within and permanently fits both of the said sockets, the opposite sides of the said handle being welded respectively to the sockets of the two plates so that the handle is rigidly connected with the plates and so that the plates are rigidly connected with each other by means of the said handle.

2. In a broom, the combination of a broom body comprising fibers, a head comprising two oppositely disposed plates in fixed relationship with each other and having their lower portions embracing and fitting the upper portion of the head, the upper portions of the said plates being shaped to provide two oppositely disposed at least partly cylindrical longitudinal sockets and the walls of the said sockets being provided with

holes near their upper ends, means for connecting the lower portion of the plates of the head with the upper portion of the broom body, a longitudinal metallic cylindrical handle the lower portion of which is within and permanently fits both of the said sockets, the opposite sides of the said handle being welded respectively to the sockets of the two plates so that the handle is rigidly connected with the plates and so that the plates are rigidly connected with each other by means of the said handle, and a collar which surrounds and fits the handle adjacent the upper ends of the sockets and which has a flange surrounding and approximately fitting the upper ends of the outer peripheries of the sockets, the

4
said flange being deformed at opposite sides thereof to provide projections which enter the socket wall holes to retain the collar in place.

ALFRED L. LE FEBVRE.
